UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,300,326.

Specification of Letters Patent. Patented Apr. 15, 1919.

Application filed October 29, 1917. Serial No. 199,040.

To all whom it may concern.

Be it known that I, JOHN H. BELL, a citizen of the United States, residing at East Orange, in the county of Essex and State of New Jersey, have invented certain new and useful Improvements in Telegraph Systems, of which the following is a full, clear, concise, and exact description.

This invention relates to telegraph systems, and more particularly to telegraph repeater systems.

The principal object of this invention is to provide an organization of apparatus for repeating telegraphic impulses from one line section into another line section in a manner to rectify the repeated impulses true to predetermined form irrespective of distorted or mutilated condition of the impulses from which translation or regeneration takes place.

A further object of this invention is to reduce the quantity of apparatus to a minimum, by an arrangement of interconnections between a limited number of electro-mechanisms in a manner to render such mechanisms capable of performing a maximum amount of work.

A feature of this invention is the provision of means for readily converting the system to operate either as an impulse-rectifying repeater or as a so-called lever or direct-point repeater.

A further feature of this invention provides means for transferring the system from the work of handling message impulses to the transmission of impulses suitable for balancing operations in connection with adjustments necessary in the maintenance of duplex equipments, or for the synchronizing of multiplex distributor stations.

In connection with telegraphic service, and particularly in the working of long lines whereon repeaters are necessary, it is well known that current impulses are acted upon by deleterious influences which have a tendency to distort, mutilate and, in particularly unfavorable situations, to cause deletion of the impulses. Such unfavorable effects may be due to extraneous causes, such as induction from adjacent circuits, the action of earth currents or from direct causes, such as inferior or varying line insulation, improper duplex balance, and numerous other transient irregularities which

may be caused by a variety of faults in the telegraphic equipment and circuits, as well understood in the art. Such phenomena or circuit irregularities may affect the impulses in different ways, a few of which may be mentioned, as either reducing or lengthening the normal period of an impulse, rendering the first or last portion of an impulse fluctuating and uncertain, varying the potential through different portions of an impulse, establishing excessive potentials for certain impulses and reduced potentials for other impulses, effecting either lead or lag in time phase relation to symmetry of transmission, and fluctuations of impulses whereby uncertainty of operation, as so-called chattering effects, are manifested in the impulse-receiving devices.

The present invention contemplates the employment of distributor means having short intervals of contact for the reception of impulses and long intervals of contact for rectification and retransmission of impulses. A plurality of electroresponsive current receptor and storing units being interconnected with the distributor means in a manner to continue relatively active in reperforming predetermined operations in connection with the reception, storing, rectifying and retransmission of impulses from one line section into another line section.

Suitable switching devices provide that the system may be readily converted into either a direct-point repeater or into an impulse-rectifying repeater.

Additional switching devices are also provided for readily conditioning the system to either operate to work message impulses or to transmit impulses of alternate polarities to enable adjustments of circuit balance to be effected.

This invention is illustrated diagrammatically in the accompanying drawings, in which only so much of a telegraphic equipment has been shown as will be necessary to a clear understanding of the present invention.

The drawing, Figure 1, illustrates an equipment suitable for a repeater station, while Fig. 2 illustrates an alternate arrangement of the equipment shown in Fig. 1.

Briefly described, the service features of the present system provide that two main line sections, designated respectively by the

reference characters 1 and 3 (Fig. 1), be terminated in duplex apparatus at A and B; the equipment located at A serves for the reception, rectification and retransmission 5 of impulses from the line 1 to the line 3, while the equipment at B operates in a similar manner to receive, rectify and retransmit impulses from the line 3 into the line 1. Since the equipments A and B are 10 typical one of the other, the same characters of reference will be employed in so far as may be expedient in designating like or similarly functioning parts.

A five-blade control or master switch unit 15 C is adapted to be operated manually in establishing the system to perform either impulse corrective repeating or direct-point repeating. A group of relays K controlled through distributor sections R, S and L 20 perform impulse storing and repeating operations.

A manually operated three-blade switching unit D serves to convert the system to substitute automatic transmission of alternate positive and negative impulses for message impulses for balancing and adjusting 25 of the duplex circuits. Ground switches 47 and 57 are employed for balancing purposes, as well understood, while telegraph keys 45 and 55 controlled by switches 44 and 54, respectively, may be employed for establishing manual or Morse service between the repeater station and respective terminal stations which may be assumed as present on 30 the lines 1 and 3. An undulator or a Wheatstone receiver 75, under control of a leak switch 74, may be connected thereby to respectively serve as a pilot impulse-receiving means for observing retransmitted impulses 35 in either direction.

In more specifically describing the features of this invention, the operations taking place for direct-point repeating will first be considered. For this service the 40 master switch C (at A) is positioned as shown in the drawing. Let it now be assumed that an impulse of positive current arrives over the line 1, whence it traverses the coils of a polarized relay 2 and an artificial line AL to earth. This current action 45 will move the armature of the polar relay to the side indicated by the conventional positive sign, whereupon a circuit will be established from a grounded source of positively 50 poled line current 63, a blade 9 of the switch C, right-hand contacts of the relay 2, blades 6 and 7 of the switch C, a conductor 43, switch 44 (in position shown), conductor 46, switch 47 (in position shown), and conductor 48 to the apex of the duplex equipment of the line 3. As well understood in 55 the art, current through this circuit divides equally through the line relay 4, one portion continuing by way of the artificial line AL to earth, while the remainder traverses the

line circuit 3 to a distant station. Neutralization of the divided currents renders them non-effective in the relay 4; the line portion is effective, however, to establishing operation of suitable receiving devices at a distant station on the line section 3. In response to a second incoming impulse from the line 1, say, of negative polarity, the relay 2 will be biased to the side indicated by the conventional negative sign, thereby completing a circuit from a grounded source of negative current 64, blade 5 of the switch C, left-hand contacts of the relay 2, thence over the path already traced to the line section 3. It will be obvious that direct-point repeating may take place from the line section 3 in a similar manner over circuits corresponding to those already traced. In repeating from the equipment at B, it may be pointed out that the repeated impulses traverse a conductor 53, switch 54, a conductor 56, switch 57 and conductor 58 to the apex or neutral outgoing point of the duplex equipment at A.

For the lever or direct-point repeating operations just described, it will be clear that the form of repeated impulses will be governed entirely by the armature of the receiving polarized relays 1 or 3; therefore distorted impulses in an originating line section will be correspondingly repeated into the second line section, except that such distortion may be increased through the repeating operations. In turn, the repeated impulses may be accumulatively acted upon by adverse conditions present in the second line section to such an extent that unsatisfactory service or perhaps complete failure of reception at a distant receiving station may result.

In describing operations whereby correction of repeated impulses is effected, let it now be assumed that the master switch C (at A) is set to its right-hand position, and that an impulse of positive current arrives over the line 1, thereby biasing the armature of the relay 2 against its positive or right-hand contact. A circuit may now be traced from a source of local current 65, the blade 9 of the switch C, contact of relay 2, blade 6 of the switch C, blade 19 of switch D, to a collector ring 10 of the distributor section R. The characters R, S and L respectively indicate receiving, sending and local sections or divisions of a distributor, and as shown may be considered as a developed view of a rotary distributor. A brush 11 adapted to travel from right to left over the distributor path 10-12 of the section R in synchronism with impulses from the line 1, may be assumed to be passing over a segment 13 in phase with the arrival of the impulse just traced to the collector ring 10. This impulse accordingly traverses the brush 11, segment 13 and a bus conductor 125

70

indicated by a like numeral, the winding of a relay 40, a bus conductor 49, thence to earth over a blade 8 of the switch C. On responding to completion of this circuit, the 5 relay 40 establishes a self-locking circuit which extends from a source of local current 66, a resistance unit 42, a bus conductor 41, and the left-hand contacts of the relay 40, continuing through the winding of this 10 relay over the circuit already traced, thereby substituting the source 66 for the source 65. Disregarding for the present the operations now taking place at the distributor sections S and L, attention will be directed at 15 once to additional impulses arriving from the line 1. Assuming that a negative impulse arrives to establish negative bias of the line relay 2, the armature of this relay will then be connected to earth over the 20 blade 5 of the switch C, and since the bus conductor 49, which serves as a common operating circuit for each of the relays K, is connected to earth at the switch C as already traced, a relay 50 remains inert or unaffected 25 ed by the brush 11 arriving over a segment 14, common to this relay, in phase with the arrival of the negative impulse from the line 1. Assuming now the arrival of a positive impulse from the line 1, the relay 2 will 30 be biased to positive, thereby completing a circuit from the local source 65 to the collector ring 10, as already traced. From this point the circuit continues over the brush 11, segment 15, a bus conductor, indicated by a 35 like numeral, the winding of a relay 60 to the grounded bus conductor 49. On operating, the relay 60 establishes a self-locking circuit from the source 66, by way of a resistance unit 62, a conductor 61, the left- 40 hand contacts of the relay 60, and the winding of this relay to the grounded bus 49. An impulse of, say, negative current from the line 1, will now bias the relay 2 to its negative side, thereby rendering the brush 45 11 ineffective at the moment it passes over a segment 16 included with a relay 70, in a manner similar to that described for the relay 50.

Directing attention to distributor section 50 S, it will be understood that a brush 21 traveling in phase with the brush 11 will have already passed over segment 23, but in passing thereover the brush 21 completed a circuit from a source of positively poled line 55 current 37, the right-hand forward contacts of the relay 40, a bus conductor 23 and a correspondingly numbered segment at S, the brush 21, collector ring 20, a conductor 39, blade 7 of the switch C, thence to the duplex 60 equipment of the line 3 over the path already traced in describing the direct-point repeating operations. A circuit next established through the distributor S extends from a negatively poled source of current 38, 65 the right-hand normal contacts of the relay

50, a bus conductor 24 and a correspondingly numbered segment at S, the brush 21 to the collector ring 20, whence the circuit extends to the line section 3, as already traced. In passing over a segment 25, the brush 21 includes the source 37 with the line 3 over circuits prepared at the relay 60 corresponding with the circuits already traced, as under control of the relay 40. In turn, the brush 21 establishes a circuit from the negative source 38 by way of circuits under control of relay 70 and segment 26 to the line 3 in a manner corresponding with the circuits already traced as controlled by the relay 50.

It will be clear that the operations just traced result in the successive reception of four alternately positive and negative impulses from the line section 1, the momentary storing of these impulses at the relays 85 K, and the substitution therefor and retransmission of impulses from the line current sources 37 and 38 to the line section 3, the retransmitted impulses being rendered perfect and corresponding in length to the 90 time required by the brush 21 in passing over respective ones of the segments in the path 22.

In taking up the operations effected by the distributor section L, it will be understood that the brush 31 of this section travels in phase with the brushes 11 and 21. Accordingly, at the moment the brush 31 arrives over a segment 33, a relay-shunting or releasing circuit will be completed from the 100 source of current 66, the resistance unit 42, blade 17 of the switch D, bus conductor 33, to the similarly numbered segment of path 32 at L, thence over the brush 31 to a grounded collector ring 30. It will be noted 105 that from the switch D the circuit just traced establishes a short-circuit on the locked winding of the relay 40, thereby permitting this relay to release. On arriving at the segment 34, the brush 31 completes a 110 circuit from a source of current 67 by way of a resistance unit 52 to earth. Since the relay 50 is inert at the present time, the establishing of its releasing shunt circuit at the section L, as described, is accordingly 115 an idle operation. The brush 31 next establishes a circuit from the source 66, the resistance unit 62, blade 18 of the switch D, a bus conductor 35 and a correspondingly numbered segment at L to the grounded collector ring 30, thereby short-circuiting and releasing the relay 60. At the segment 36, 120 although the brush 31 grounds the source 67 through a resistance unit 72, no action takes place since the corresponding relay 125 70 is now inert, as described.

It will be noted that the segments of the path 12 at distributor section R are small as compared with the segments of the paths 22 and 32 of sections S and L, respectively, 130

and occupy the middle portion only of the available space. This reduced length and central positioning of the segments at R result in utilization of the central portion 5 only of an impulse arriving from the line section 1. Elimination of the first and last portions of an impulse insures that the least mutilated part, which is ordinarily the central portion, will be effective through the 10 repeater. The method of interconnecting the relays K between the receiving distributor section R and the sending section S provides that the connections be arranged to give the section R an advance or lead 15 of one segment, as compared with the correspondingly associated segment in the section R. This insures that each relay of the group K will have ample time to operate and come to rest or "settle" before the line 20 battery controlled thereby is transmitted by the distributor section S. In turn, the interconnections between the relays K and the local or releasing distributor section L, provide that corresponding connections to 25 the segments of the path 32 will fall one segment to the rear of the segments of path 22 on the section S. This permits ample time for a stored impulse to be transmitted through the repeating or sending section S 30 in advance of an associated storing relay being released through the section L.

In the matter of lead between the three distributor sections, it will be apparent that the same relative results may be attained 35 by interconnecting the relays K to correspondingly associated segments in direct alinement with relation to the three sections R, S and L, and correspondingly positioning or setting the three brushes in such a 40 manner that the brush 21 will travel one segment to the rear of brush 11, and in turn brush 31 will follow one segment behind the brush 21.

At the path 12 of section R, each of the 45 four conductors 13, 14, 15 and 16 connect in derived circuit to alternate fifth segments, the conductors 23, 24, 25 and 26 connect in a similar order to the segments of path 22 at S, while the conductors 33, 34, 50 35 and 36 connect in a like manner to the segments of path 32 at L. Since each distributor section is provided with twenty segments, it will be apparent that twenty incoming impulses from the line 1 may 55 be received during the time the brushes 11, 21 and 31 are traversing their associated twenty segments. Assuming that twenty successive positive impulses are received from the line 1, each of the relays K would ac- 60 cordingly respond five times, send out a repeated positive impulse through the section S five times, and be released five times through control of the section L.

It will be understood that the impulses re- 65 peated may be of any suitable code unit com-

bination, such as the five-unit code of Bau-
dot, which is suitable for operating telegraph
printers.

Incoming messages from the line section 3 are translated into the line section 1 through 70 the equipment B, which, as already mentioned, is typical of the equipment A, in a manner similar to that already described, for the repeating operations from the line 1 to the line 3. Repeating operations in one 75 direction are independent of repeating operations in the other direction, therefore, messages may be undergoing direct-point re-
peating one way, at the same time that re-
peating is progressing by the "brush" or 80 impulse-correcting method in the other di-
rection.

Referring to the switch D, by manually moving this switch to its right-hand position, the blade 19 disconnects the collector ring 10 of the distributor section R, while blade 17 disconnects the plurality of segments 33 of the path 32 at section L and connects the source of current 66 through the resistance unit 42, the conductor 13 and 90 winding of the relay 40 to the conductor 49, grounded over the blade 8 of the switch C, which must also be in its right-hand position at this time. The blade 18 of the switch D disconnects the plurality of 95 segments 35 at the distributor section L, and includes the source of current 66, through the resistance unit 62, conductor 15 and the winding of the relay 60 to the grounded conductor 49. It will be clear that the two cir-
cuits just traced from the source 66 will re-
tain the relays 40 and 60, respectively, oper-
ated, while the operating circuits for the 100 two relays 50 and 70 will continue disabled
through the disconnected condition of the collector ring 10, as described. During the period the equipment continues in the position described, the brush 11 at R travels idly through its regular path, while the brush 21 at S transmits alternate positive 110 and negative impulses to the line 3. Such alterna-
tions of current correspond with the actuated position of the relays 40 and 60, whereby the positively poled source of current 37 is included with respective pluralities 115 of segments 23 and 25 of the path 22 at S, while the inert condition of the relays 50 and 70 includes the source of negative current 38 with the respective pluralities of segments 24 and 26 of the path 22 at S. In the matter 120 of service results, the brush 31 at L travels idly through its usual path during such transmission of alternately positive and negative impulses.

Referring to Fig. 2 of the drawing, the 125 alternate arrangement shown therein is in general the same as the arrangement shown in Fig. 1. The difference between the two systems is present in the employment of five relays K instead of four relays as shown in 130

the first arrangement, increasing the number of segments in each of the paths 12, 22 and 32 of the distributor to twenty-five (although it will be obvious that any number 5 of segments forming an even multiple with five may be employed), and dispensing with the switch D and the service covered thereby. In considering this alternate arrangement, it will be understood that it represents an 10 equipment which may be substituted for either the A or the B portion of the equipment shown in Fig. 1, or each of the latter equipment groups may be replaced by a group in accordance with the alternate ar- 15 rangement.

For convenience of comparison, corresponding characters of reference or uniform progressions thereof have been employed to indicate similar parts in each figure of the 20 drawing. Therefore, by assuming a substitution of Fig. 2 for the portion A of Fig. 1, it will be obvious that an understanding of the foregoing description of the first arrangement will render an inspection of the 25 drawings so combined sufficient to establish a clear understanding of the alternate arrangement. Accordingly, detailed or further description of the alternate arrangement will not be necessary.

30 What is claimed is:

1. In a telegraph repeater system, sources of current, distributor equipment comprising several segmented divisions and a plurality of relays each interconnected to be 35 effective from a plurality of segments on each of the distributor divisions, a plurality of line sections, means effective through said distributor equipment to repeat telegraphic impulses between said line sections, and 40 switching means to permit repeating operations to be carried on between said line sections independently of said distributor equipment.

2. In a telegraph system, the combination 45 with a plurality of line sections; sources of current; distributor equipment comprising three segmented divisions respectively corresponding with receiving, sending and clearing out operations, and a plurality of 50 relays each interconnected to be effective from a plurality of segments in each of said distributor divisions; and means effective through said distributor equipment for repeating telegraphic impulses between said 55 line sections.

3. The combination with a plurality of 60 duplexed telegraph lines, of a repeater station therefor comprising sources of current and for each of said lines a plurality of sequentially operated contactor divisions, electroresponsive switching means interconnected between pluralities of the contactors in each of said contactor divisions, impulse receiving means for each of said lines to 65 jointly act with respectively associated ones

of said contactor divisions and said electroresponsive switching means to repeat telegraphic signals between said lines, and switching means to disable said electroresponsive switching means in enabling predetermined ones of said contactor divisions to transmit predetermined changes of potential from said sources of current to said lines in substitution of said repeating operations. 70

4. The combination with a plurality of telegraph lines; source of current; distributor equipment comprising three sequentially operated contactor divisions corresponding with receiving, sending and clearing out operations, and a plurality of relays each interconnected to be effective from a plurality of the contactors on each of said distributor divisions; means jointly effective with said distributor equipment for repeating telegraphic impulses between said lines; and means controlled by said clearing out distributor division for disabling said relays. 75

5. In combination with a first and second telegraph line, a repeater station comprising sources of current, a line relay for the first line, a multipoint distributor equipment including a plurality of storing relays jointly active with said line relay for repeating telegraphic impulses from said first to 90 said second line, means for interconnecting each of said storing relays in order that each action thereof may be effective from respective pluralities of points on said distributor, and shunt paths controlled by said distributor equipment for disabling said storing relays. 100

6. In a telegraph repeater system, sources of current, a plurality of line sections, distributor means comprising a plurality of segmented contactor paths, a plurality of relays each interconnected to operatively respond from a plurality of segments in a first one of said contactor paths, means controlled by each one of said relays to vary the current condition at a plurality of segments on a second one of said contactor paths, line relay means jointly active with said distributor means to repeat telegraphic impulses between said line sections, and a plurality of shunt paths each effective from a plurality of segments on a third one of said distributor sections for respectively disabling said relays. 110

7. In combination with a plurality of telegraph lines, of a repeater station providing a first and second method of repeating telegraphic impulses between said lines, sources of current, impulse receiving means responsive to current changes in one of said lines, 120 means controlled by said impulse receiving means to establish corresponding current changes in another one of said lines comprising the first repeater means, distributor equipment comprising sequentially operated 125

130

contacts and relays controlled thereby to form the second repeating means, and means to transfer the action of said impulse receiving means to become effective through 5 said distributor equipment in repeating telegraphic impulses between said lines.

8. In combination with a plurality of duplexed telegraph lines, of a repeater station therefor, impulse receiving means for each 10 of the lines, sources of current, distributor means and a plurality of electroresponsive switching devices controlled by said distributor means for each of said lines, means controlled by said impulse receiving means to 15 act jointly with the respectively associated distributor means and the electroresponsive switching devices to repeat telegraphic impulses between said lines, and means for conditioning said distributor means and said 20 electroresponsive switching means effective to transmit uniformly recurring combinations of impulses in substitution of repeated message impulses.

9. In a telegraph repeater system, sources 25 of current, a first line section, a line relay therefor, a plurality of relays, a first distributor means, means jointly controlled by said line relay and said first distributor means for selectively controlling the operation 30 of said plurality of relays in a manner corresponding with telegraphic impulses in said first line section, second distributor means, means controlled by said plurality of relays for selectively establishing changes 35 of current with said second distributor means corresponding with impulses in said first line section, a second line section, means for transmitting the described current changes from said second distributor means 40 to said second line section, a third distributor means for disabling said plurality of relays, and means for interconnecting said plurality of relays to be respectively effective from a plurality of points on each of 45 said distributor means.

10. In a telegraph repeater system, sources of current, a first line circuit, a first distributor section comprising a plurality of sequentially operated contacts, a plurality 50 of relays each interconnected to a plurality of the contacts of said first distributor section, a line relay controlled by impulses in said first line circuit acting with said first distributor section to selectively control the 55 operation of said plurality of relays, a second distributor section comprising a plurality of sequentially operated contacts, means controlled by each of said plurality of relays to establish current changes on a 60 plurality of the contacts on said second distributor section, a second line circuit, means for transmitting the described current changes from said second distributor section to said second line circuit, a third distributor 65 section comprising a plurality of sequen-

tially operated contacts, and means controlled from respective pluralities of the contacts on said third distributor section for short-circuiting the operating circuit of each one of said plurality of relays.

11. In combination with a first and a second telegraph line, direct-point repeater equipment comprising a line relay, and means controlled by said line relay for repeating telegraphic impulses from said first 75 to said second line, a distributor equipment comprising a plurality of sections and a plurality of relays each interconnected to be effective from a plurality of points on each section of said distributor, and means for transmitting said line relay from direct-point repeating to act jointly with said distributor equipment in the reception, storing, regenerating and retransmission of impulses in repeating signals from the first to the second 80 line section.

12. In a telegraph repeater system, sources of current, distributor equipment comprising several sections each provided with a plurality of sequentially operated contacts 90 and a plurality of relays each interconnected to be effective from a plurality of the contacts in each one of said sections, a first and a second telegraph line, means jointly active with said distributor equipment for repeating telegraphic impulses from said first to said second line, and means for continuing a disabled condition of certain ones and an operated condition of certain other ones of said 95 plurality of relays to transmit impulses of alternating polarities in substitution of repeated impulses.

13. In a telegraph repeater system, sources of current, a distributor equipment comprising a plurality of segmented contactor paths, a plurality of relays each interconnected to pluralities of segments in each of the contactor paths, a resistance unit connected in the operating circuit of each of the relays, a first and a second telegraph line, means jointly active with a first and second contactor path of said distributor equipment for repeating impulses from said first to said second line section, and means controlled by a third contactor path of said distributor 105 equipment to short-circuit the operating circuit of each of said relays.

14. In combination with a first and second telegraph line, distributor equipment comprising several sequentially operated contactor divisions corresponding with receiving, sending and clearing out operations, a plurality of relays, means for including each one of said relays to be operated at one moment through said receiving division, at a later moment to be effective with said sending division and at a still later moment to be disabled by said clearing out division, a plurality of line sections, and means effective through said distributor equipment and 110 115 120 125 130

said relays to repeat telegraphic signals between said first and second telegraph lines.

13. In a telegraph repeating system, sources of current, distributor means comprising several segmented sections corresponding with receiving, sending and clearing out operations, a plurality of line sections, a plurality of relays each interconnected to serve in the receiving, sending and clearing out

operation as carried out at different moments through said distributor divisions, and means effective through said distributor means and said relays for repeating telegraphic signals between said line sections.

In witness whereof I hereunto subscribe 15 my name this 24th day of October, A. D. 1917.

JOHN H. BELL.
